E. J. WILKIE, P. S. STEVENS AND W. LEHMAN,
DIPPER TRIPPING MECHANISM.
APPLICATION FILED MAR. 31, 1919.

1,376,181.

Patented Apr. 26, 1921.

UNITED STATES PATENT OFFICE.

EDWIN J. WILKIE, PAUL S. STEVENS, AND WERNER LEHMAN, OF SOUTH MILWAUKEE, WISCONSIN, ASSIGNEES TO BUCYRUS COMPANY, OF SOUTH MILWAUKEE, WISCONSIN, A CORPORATION OF WISCONSIN.

DIPPER-TRIPPING MECHANISM.

1,376,181.

Specification of Letters Patent. Patented Apr. 26, 1921.

Application filed March 31, 1919. Serial No. 236,604.

To all whom it may concern:

Be it known that we, EDWIN J. WILKIE, PAUL S. STEVENS, and WERNER LEHMAN, being citizens of the United States, and residents of South Milwaukee, in the county of Milwaukee and the State of Wisconsin, (whose post-office address is care of Bucyrus Company, South Milwaukee, Wisconsin,) have invented a certain new and useful Improvement in Dipper-Tripping Mechanism, of which the following is a specification.

Our invention relates to improvements in dipper tripping mechanism for steam shovels and the like and is particularly adapted for use in connection with the larger type of shovels where the weights carried are so great and the parts so cumbersome, that the mere act of tripping the bottom of the bucket for discharging the load becomes so great a burden on the operator as to decrease the speed and accuracy of operation.

One object therefore is to provide power actuated means controllable by the operator for tripping the bucket, thus doing away in some instances with the need of a special man to perform that function.

Other objects will appear from time to time in the specification.

Our invention is illustrated more or less diagrammatically in the accompanying drawings, wherein,

Figure 1 is a side elevation with parts broken away, of a steam shovel equipped with our device.

Fig. 2 is a detailed section on a large scale along line 2—2 of Fig. 3.

Fig. 3 is a side view with parts broken away, of the power tripper shown in Fig. 2.

Fig. 4 is a perspective of a modified form of means for holding the tripping line taut.

Like characters indicate like parts in the figures.

A is an inclosed working platform mounted for rotation on a movable base, A¹. It contains the usual steam shovel operating and controlling apparatuses and mechanisms. A² is a boom pivoted on the platform A and held in inclined working position by the lines A³.

B is a dipper handle slidable in the stirrup B¹ which stirrup is pivotally mounted for rotation about the shipper shaft B². B³ is a rack on the handle B, engaging a suitable gear which is driven through a chain

of gears B⁴ by the engine B⁵ on the boom A², whereby the dipper handle may be laterally displaced.

C is a dipper mounted on the end of the dipper handle B. C¹ is a bail engaging a hoisting cable C² which passes over a sheave C³ on the end of the boom, thence extends down to the hoisting mechanism on the platform A. C⁴ is a bucket bottom or door closed and locked by a latch C⁵ which latch may be released by tension on the chain C⁶. This tension is provided by rotation of the lever C⁷. C⁸ is the trip line anchored at one end on the lever C⁷, passing over a pulley C⁹ on the boom A² and extending thence down to the working platform A.

D is a turbine housing mounted on the platform A. It contains an impulse wheel D¹ mounted on the shaft D². D³ is a pulley on that shaft about which the cable C⁸ is wound. D⁴ is a coil spring anchored at one end on a pin D⁵ on the outside of the housing D, engaging at the other end in the slotted end of the shaft D², the parts being so arranged that the spring keeps the line C⁸ taut at all dumping positions of the bucket. D⁶ is a nozzle adapted to discharge steam, water or other motive fluids against the buckets on the wheel. This nozzle is supplied with the motive fluid through the pipe D⁶ and controlled by a valve D⁷ near the hand of the operator. This motive fluid may be supplied by the boiler or by any other suitable source. D⁸ is the exhaust pipe through which the spent motive fluid may pass.

In Fig. 4 the modified form shown, illustrates the use of a weight rather than a spring. Obviously the result would be the same.

I have shown a turbine motor arranged to exert tension on the tripping cord. Obviously other means may be provided for pulling on the cord without departing materially from the spirit of my invention. Many other changes might also be made in size, shape and arrangement of parts and it will be understood, therefore, that my drawings are in a very real sense diagrammatic though they do illustrate in sufficient detail an operative device.

The use and operation of my invention are as follows:—

The steam shovel is manipulated for exca-

vation in the usual way by a shovel man who sits or stands on the working platform where he can see and control everything.

When he wants to dump the bucket load, 5 instead of pulling on the cord by hand according to the usual practice, he merely works the lever or throws the clutch or does whatever has to be done to start the tripping engine which in this case is a turbine. The 10 tripping engine winds up on the rope, rotates the lever and dumps the load.

The weight and length of the trip line furnishes the necessary elasticity to cushion the shock of the starting of the tripping engine 15 and the spring or weight or other means which keeps the tripping rope relatively tight at all times makes sure that response to the tripping engine will be immediate.

The engine which I prefer to use is a 20 turbine because as soon as the tripping action is complete and the steam turned off, the rope can be pulled out to conform to the bucket movements without material resistance on the part of the engine. But this 25 engine might be of other types or there

might be a ratchet action so that any form of engine or motive means is appropriate.

I claim:

A dipper latch tripper device comprising a rotary impulse wheel connected to a winding drum, a cable wound about said drum, tension means acting through said drum to keep the cable taut, but not tight enough to trip the dipper latch, said tension means comprising a torque spring concentric with 35 said rotary impulse wheel, a fluid pressure means acting against said rotary impulse wheel at the will of the operator whereby tension of the cable may be increased sufficiently to trip the dipper latch. 40

In testimony whereof, we affix our signatures in the presence of two witnesses this 15th day of March, 1919.

EDWIN J. WILKIE.
PAUL S. STEVENS.
WERNER LEHMAN.
